UNITED STATES PATENT OFFICE

ALBERT EDWARD ATKINSON, OF UPPER BURMA, BRITISH INDIA

DRILLING OF OIL WELLS AND THE LIKE

Application filed November 11, 1930, Serial No. 494,945, and in Great Britain February 7, 1930.

In the drilling of oil wells and the like, it is found in practice that the hole may become crooked or out of the perpendicular, and it is a very difficult and tedious matter to form a shoulder at the side of the crooked hole in order that the drilling bit may be enabled to proceed in a vertical direction.

The object of my present invention is to provide a simple and efficient method of and 10 means for correcting a hole which has been bored out of the perpendicular and for enlarging producing wells.

In accordance with my invention, when it is found that a crooked hole is being bored, a 15 jet fitting which may comprise a number of radial nozzles or apertures is attached to the drill collar and fluid under pressure is delivered therethrough to scour out the bore already made. The scouring action is started 20 some distance from the bottom of the crooked hole and the drilling bit and jet fitting slowly rotated and raised. The débris will circulate out of the bore hole with the hydraulic fluid. The process is repeated as many times 25 as may be found necessary. After each operation, the drill pipe will be enabled to hang more nearly vertical and the drill at the bottom of its movement will prepare a shoulder beneath the vertical hole so that a new hole 30 can be formed therein. A similar method and similar means may be employed to enlarge a producing well.

Referring to the accompanying sheet of explanatory drawings:—

Figure 1 illustrates diagrammatically a bore hole being straightened, with different stages in the straightening operation indicated.

Figure 2 is an elevation, Figure 3 a plan view and Figure 4 a sectional elevation of the jetting head in accordance with this invention.

The jetting head *a* is adapted to be screwed at *b* into the drill pipe or stem *c*. Such head has, in the illustrated examples, four projecting arms *d* in each of which is arranged a nozzle *e* through which fluid, usually muddy water, is projected from the drill pipe on to the wall of the bore hole. The nozzles are renewable. The upper and lower sides of the

arms *d* have preferably cutting edges *f* provided thereon, such edges being formed of suitable cutting steel applied to the arms by welding or otherwise.

Referring to Figure 1, *g* indicates a 55 crooked bore hole which it is desired to correct. The drill pipe is withdrawn and the jetting head shown in Figures 2 to 4 substituted for the ordinary drilling bit. The said head is now lowered into the bore hole 60 but not to the depth of the hole *g*. It may be lowered to, say, a point 10 feet from the bottom of *g* so that a new shoulder *h* can be formed through which the correct or straightened bore hole indicated by dotted 65 lines at *i* can be bored. At the said distance of 10 feet from the bottom of *g* the jetting operation is commenced, the drill pipe being rotated and causing the jetting fluid which is under considerable pressure to impinge with great force upon the wall of the bore hole and scour and disintegrate the surface material which will be washed away up the bore hole by the fluid which overflows at the top of the hole. As the drill pipe 70 tends to assume a vertical position, the scouring and disintegrating action is the most pronounced at the side of the crooked bore hole which has to be eaten into in order to correct the hole for verticality. During the jetting, 75 the drill pipe and jetting head are gradually raised so that the correcting action can take place right up the bore hole to where the deviation from the vertical originally occurred. The operation is repeated as often 80 as may be necessary, the jetting being continued from the new shoulder *h* up to where the error has originated until the drill pipe hangs quite vertically, when the drill pipe 85 can be removed, and the jetting head substituted by the usual drilling bit and the latter brought to operate on the new shoulder *h*. In Figure 1, the dotted line *j* indicates the possible degree of correction of the bore hole after one upward traverse of 90 the jetting head, and *k* indicates the possible degree of correction after two traverses. When the new wall *h* is formed, a drill pipe 95 with drilling bit to produce the vertical bore *i* through *h* can be used.

The cutting edges *f* enable the jetting head to cut through any material which may "fall in" upon the tool from the walls of the bore hole.

5 The jetting head may have any desired number of arms *d* with nozzles therein and may be of any convenient shape.

My improved method and means may be employed to enable a straight hole to be bored 10 to sidetrack a crooked hole containing, for example, a broken bit or other obstruction, commonly termed a "fish". The jetting fitting may also be employed for enlarging the diameter of producing wells by scouring out the oil sand around the bore hole.

15 What I claim is:—

The method of correcting oil well bore holes which consists in jetting the walls of the already produced bore hole by radially 20 disposed fluid jets upon the drill pipe the jetting commencing at a point above the bottom of the crooked bore hole to produce a new shoulder and continuing upward to where the crookedness commenced, the said 25 shoulder being extended until the drill pipe hangs vertically, after which the jetting head is replaced by the usual drilling bit and the latter brought to operate on the newly formed shoulder.

30 In testimony whereof I have signed my name to this specification.

ALBERT EDWARD ATKINSON.
